(57) **CLAIM**

The ornamental design for a vial, as shown and described.

DESCRIPTION

FIG. 1 is an exploded perspective view of a vial according to our new design;

FIG. 2 is a front elevational view of the vial of FIG. 1 partially assembled;

FIG. 3 is a front elevational view of the vial of FIG. 1 fully assembled;

FIG. 4 is a bottom plan view thereof;

FIG. 5 is a top plan view of the partially assembled vial of FIG. 2;

FIG. 6 is a top plan view of the fully assembled vial of FIG. 3; and,

FIG. 7 is an overhead perspective view of the fully assembled vial of FIG. 3.

In the drawings, the broken lines in FIG. 4 depict portions of the design that form no part of the claim.
